(57) **CLAIM**

The ornamental design for an arc flash helmet as shown and described.

DESCRIPTION

FIG. 1 is a top front perspective view of an arc flash helmet, according to the present design.

FIG. 2 is a front elevation view of the arc flash helmet of FIG. 1.

FIG. 3 is a rear elevation view of the arc flash helmet of FIG. 1.

FIG. 4 is a right-side elevation view of the arc flash helmet of FIG. 1.

FIG. 5 is a left-side elevation view of the arc flash helmet of FIG. 1.

FIG. 6 is a top plan view of the arc flash helmet of FIG. 1.

FIG. 7 is a bottom plan view of the arc flash helmet of FIG. 1; and,

FIG. 8 is a top front perspective view of the arc flash helmet of FIG. 1, with the visor in an open state.

The broken lines in the drawings depict portions of the arc flash helmet that form no part of the claimed design.

1 Claim, 8 Drawing Sheets
